CLAIM

The ornamental design for an access device, as shown and described.

DESCRIPTION

FIG. 1 is a front side perspective view of an access device configured in accordance with a preferred embodiment of the present invention;

FIG. 2 is a top view of the access device shown in FIG. 1;

FIG. 3 is a first side view of the access device shown in FIG. 1, the other side being a mirror image of the first side;

FIG. 4 is a bottom view of the access device shown in FIG. 1;

FIG. 5 is a first end view of the access device shown in FIG. 1;

FIG. 6 is a second end view of the access device shown in FIG. 1;

FIG. 7 is a front side perspective view of an access device configured in accordance with another preferred embodiment of the present invention;

FIG. 8 is a top view of the access device shown in FIG. 7;

FIG. 9 is a first side view of the access device shown in FIG. 7, the other side being a mirror image of the first side;

FIG. 10 is a bottom view of the access device shown in FIG. 7;

FIG. 11 is a first end view of the access device shown in FIG. 7;

FIG. 12 is a second end view of the access device shown in FIG. 7;

FIG. 13 is an enlarged view of the access device shown in FIG. 8, at 13—13;

FIG. 14 is an enlarged view of the access device shown in FIG. 9, at 14—14; and,

FIG. 15 is an enlarged view of the access device shown in FIG. 10, at 15—15.

Phantom lining, where utilized, is for illustrative purposes only and does not limit or form any part of the claimed design.
